UNITED STATES PATENT OFFICE.

WILLIAM O. MC ELROY AND JOSEPH F. TROPEA, OF RIVEREDGE, NEW JERSEY.

AMUSEMENT DEVICE.

Application filed February 8, 1924. Serial No. 691,482.

To all whom it may concern:

Be it known that we, WILLIAM O. MC ELROY and JOSEPH F. TROPEA, citizens of the United States, residing at Riveredge, 5 in the county of Bergen and State of New Jersey, have invented new and useful Improvements in Amusement Devices, of which the following is a specification.

This invention relates to amusement devices or games and has for an object the provision of a device which in addition to providing amusement, is attractive and instructive and may be used for playing many different games.

15 With the above and other objects in view, the invention further includes the following novel features and details of construction, to be hereinafter more fully described, illustrated in the accompanying drawings 20 and pointed out in the appended claims.

In the drawings:—

Figure 1 is an elevation of an amusement device constructed in accordance with the invention.

25 Figure 2 is a top plan view of the same. Figure 3 is a longitudinal vertical sectional view.

Figure 4 is a vertical transverse sectional view on the line 4—4 of Figure 3.

30 Figure 5 is a horizontal section.

Figure 6 is a detail elevation showing the clutch in released position.

Figures 7 and 8 are detail views.

35 Referring to the drawings in detail wherein like characters of reference denote corresponding parts, the device as shown comprises a box-like housing which includes sides and ends 10 and 11 respectively, a bottom 12 and a top or platform 13. The casing may be made of any suitable size 40 and material and is preferably of knock-down construction, the parts being removably secured together by fastening devices 14.

45 The platform 13 is provided with an annular slot 15, the central portion 16 of the platform being supported by a standard 17 which rises from the bottom 12. The outer portion of the platform has its inner edge braced by suitable brackets 18 which extend from the sides 10 and ends 11 of the casing.

50 Mounted within bearings 19 which rise from the bottom 12 of the casing is a sectional shaft 20. The adjacent ends of this shaft are adapted to be connected by a nor-

mally engaged spring actuated friction clutch 21. The shaft 20 is driven by any suitable means, such as a motor 22, the latter being operatively connected with the shaft by means of gears 23. The inner end of the shaft 20 carries a pinion 24 which engages and drives a ring gear 25. This gear 25 is rotatable about the standard 17, suitable anti-friction bearings being provided for this purpose.

Secured to the ring gear 25 is an arm 26 which extends upwardly and outwardly through the slot 15 of the platform and which has secured thereon a toy automobile 27, or other vehicle or container.

The motor 22 may receive current from any suitable source of power, or, it may be in the form of a spring motor and when the shaft 20 is rotated, it will be seen that the automobile 27 will move over the surface of the platform, due to the arm 26 which connects the automobile with the ring gear 25.

Supported above the platform by any suitable means is a container, preferably in the form of a house 28, the latter being provided with a spring actuated normally closed door 29. Located within this house is a horizontally rotatable floor or bottom 30 which is supported upon the upper end of a vertically disposed shaft 31. The shaft 31 extends downward through the platform 13 and is supported in upper and lower bearings 32, the bearings being in turn supported by arms or brackets 33. The shaft 31 is operatively connected to the shaft 20 by gearing 34, so that when the last mentioned shaft is rotated rotation will be imparted to the vertical shaft 31 so that the bottom or floor 30 will be likewise rotated. Located within the container or house 28 is a number of movable elements or balls 35 which contain suitable indicia. This indicia may be in the form of numbers or letters or both, the object being to automatically open the door 29 of the house when the automobile reaches a proper position, whereupon rotation of the bottom or floor 30 will cause one of the balls 35 to pass through the door and through a chute 36 leading therefrom, into the automobile.

For this purpose the automobile is automatically stopped at a proper point adjacent the discharge end of the chute 36 and to accomplish this, the shaft 20 is provided with a relatively long worm section 37. This sec-

tion 37 is engaged by a split nut 38 whose sections are hingedly secured together as at 39. These nut sections are arranged to engage the worm 37 so that when the shaft 20 is rotated, the nut will travel along the shaft in a direction away from the clutch 21. Secured to each section of the nut 38 are links 40, while one member of the clutch has secured thereto links 41. The links 40 and 41 are pivotally connected together so that as the nut travels away from the clutch 21, the links will straighten out and when the limit of this straightening action occurs, the clutch will be disengaged against the action of its spring so that one section of the shaft 20 will cease to rotate and travel of the automobile will stop.

Also extending from the movable member of the clutch 21 is an arm 42, while connected to this arm through the medium of a rod 43 is one end of a pivotally mounted lever 44. The opposite end of this lever engages the door 29, so that as the clutch moves to a disengaged position, pivotal movement will be imparted to the lever 44 and the door 29 will be opened against the action of its spring a sufficient distance to permit of the passage of one of the balls 35.

From the foregoing description and accompanying drawings it will be seen that through the power of the motor 22, the shaft 20 will be operated to move the automobile over the platform as previously described and the ratio of the pinion 24 and gear 25 and the length of the worm 27 is such that the automobile will complete a number of circuits around the platform before coming to a standstill, that is before the clutch is released. When this releasing action occurs, the lever 44 will be actuated to open the door 29 so that one of the balls will enter the automobile. In order to accurately time the opening of the door with the stopping of the automobile, the links 41 are constructed so that their lengths may be regulated as indicated at 45.

After the ball has entered the automobile, the clutch may be re-engaged by means of a resetting lever 46. This lever is pivotally mounted upon the outside of the casting and has connected thereto one end of a rod 47. The opposite end of this rod is connected to a nut 38 and is provided with a member 39 whereby, inward movement of the rod 47 will move the sections of the nut 38 upon their pivot so that the nut will be disengaged from the worm. Further inward movement will cause the nut to move toward the clutch 21 until it reaches its initial or starting position. At this point the member 34 will be disengaged and the nut re-engaged with the worm.

In playing a game, the players may operate the device in turn and one or any predetermined number of turns may be de-

termined upon for each player, the player whose numbered balls total the highest number of points winning the game. As constructed, the outcome of the game is entirely controlled by chance, so that each player 70 has an equal opportunity to win.

It is preferred to construct the house or container 28 of some transparent material, so that movement of the balls upon the rotating bottom may be seen, the balls continuing to move both while the automobile is in motion and while it is idle.

The invention is susceptible of various changes in its form, proportions and minor details of construction and the right is 80 herein reserved to make such changes as properly fall within the scope of the appended claims.

Having described the invention what is claimed is:

1. In an amusement device, a horizontally movable member, means whereby the member may be moved including a power shaft, a container located adjacent the path of movement of said member, movable elements within the container, means for operating said power shaft, means including a split nut operatively engaging the shaft to automatically stop the movable member adjacent the container, means for automatically releasing one of the elements from the container and ejecting the same into the movable member when the latter is stopped and means whereby the parts may be returned to normal position. 90

2. In an amusement device, a horizontally movable member, a container located adjacent the path of movement of said member, means including an operating shaft whereby the member may be moved, a clutch for controlling the shaft, means controlled by the operation of the shaft for controlling the clutch, whereby the movable member will be automatically stopped adjacent the container, movable elements within the container and means for automatically releasing one of the movable elements from the container and directing the same into the movable member. 100

3. In an amusement device, a horizontally movable member, a container located adjacent the path of movement of said member, means including an operating shaft whereby the member may be moved, a clutch for controlling the shaft, means controlled by the operation of the shaft for controlling the clutch, whereby the movable member will be automatically stopped adjacent the container, movable elements within the container and means controlled by the clutch controlling means for automatically releasing one of the movable elements from the container and directing the same into the movable member. 115

4. In an amusement device, a horizontally 130

- movable member, a container located adjacent the path of movement of said member, means including an operating shaft whereby the member may be moved, a clutch for controlling the shaft, means including a nut operatively engaging the shaft and connected with the clutch for automatically actuating the latter to stop the movable member adjacent the container, movable elements within the container and means for automatically releasing one of the movable elements from the container and directing the same into the movable member.
5. In an amusement device, a horizontally movable member, means whereby the member may be moved, a container located adjacent the path of movement of said member, a rotatable bottom for the container, means whereby the bottom may be rotated, spherical elements within the container and means whereby the movable member will be automatically stopped adjacent the container and one of the spherical elements released from the latter and directed into the movable member.
10. Within the container and means for automatically releasing one of the movable elements from the container and directing the same into the movable member.

5. In an amusement device, a horizontally movable member, means whereby the member may be moved, a container located adjacent the path of movement of said member and having an opening therein, a spring closed door for the opening, movable elements within the container, a rotatable bottom for the container, whereby the elements may be moved for passage through the opening, means whereby the movable elements will be automatically stopped adjacent the
15. movable member, means whereby the member may be moved, a container located adjacent the path of movement of said member, a rotatable bottom for the container, means whereby the bottom may be rotated, spherical elements within the container and means whereby the movable member will be automatically stopped adjacent the container and one of the spherical elements released from the latter and directed into the movable member.
20. An amusement device comprising a housing, a member movable over the housing and adapted to travel in a circular path, means whereby the member may be moved, a container supported above the housing adjacent the path of movement of the movable member, a plurality of movable elements within the container and means located within the housing for automatically releasing said elements singly and at intervals for deposit within the movable member when the latter reaches a position adjacent the container.
25. An amusement device comprising a housing, a member movable over the housing, means whereby the member may be moved, a container supported above the housing adjacent the path of movement of the movable member, a plurality of movable elements within the container and means located within the housing for automatically releasing said elements singly and at intervals for deposit within the movable member when the latter reaches a position adjacent the container and means whereby the length of intervals between the release of the movable elements may be regulated.

30. An amusement device comprising a housing, a member movable over the housing and adapted to travel in a circular path, means whereby the member may be moved, a container supported above the housing adjacent the path of movement of the movable member, a plurality of movable elements within the container and means located within the housing for automatically releasing said elements singly and at intervals for deposit within the movable member when the latter reaches a position adjacent the container.

35. An amusement device comprising a housing, a member movable over the housing, means whereby the member may be moved, a container supported above the housing adjacent the path of movement of the movable member, a plurality of movable elements within the container and means located within the housing for automatically releasing said elements singly and at intervals for deposit within the movable member when the latter reaches a position adjacent the container.

40. An amusement device comprising a housing, a member movable over the housing, means whereby the member may be moved, a container supported above the housing adjacent the path of movement of the movable member, a plurality of movable elements within the container and means located within the housing for automatically releasing said elements singly and at intervals for deposit within the movable member when the latter reaches a position adjacent the container.

45. An amusement device comprising a housing, a member movable over the housing, means whereby the member may be moved, a container supported above the housing adjacent the path of movement of the movable member, a plurality of movable elements within the container and means located within the housing for automatically releasing said elements singly and at intervals for deposit within the movable member when the latter reaches a position adjacent the container.

50. An amusement device comprising a housing, a member movable over the housing, means whereby the member may be moved, a container supported above the housing adjacent the path of movement of the movable member, a plurality of movable elements within the container and means located within the housing for automatically releasing said elements singly and at intervals for deposit within the movable member when the latter reaches a position adjacent the container.

55. An amusement device comprising a housing, a member movable over the housing, means whereby the member may be moved, a container supported above the housing adjacent the path of movement of the movable member, a plurality of movable elements within the container and means located within the housing for automatically releasing said elements singly and at intervals for deposit within the movable member when the latter reaches a position adjacent the container.

60. An amusement device comprising a housing, a member movable over the housing, means whereby the member may be moved, a container supported above the housing adjacent the path of movement of the movable member, a plurality of movable elements within the container and means located within the housing for automatically releasing said elements singly and at intervals for deposit within the movable member when the latter reaches a position adjacent the container.

65. An amusement device comprising a housing, a member movable over the housing, means whereby the member may be moved, a container supported above the housing adjacent the path of movement of the movable member, a plurality of movable elements within the container and means located within the housing for automatically releasing said elements singly and at intervals for deposit within the movable member when the latter reaches a position adjacent the container.

In testimony whereof we have affixed our signatures.

WILLIAM O. McELROY.
JOSEPH F. TROPEA.
